PRESSURE COMPENSATED PUMP

James K. Douglas, Shorewood, Wis., assignor to
The Oilgear Company, Milwaukee, Wis., a corporation of Wisconsin

Application March 27, 1950, Serial No. 152,256

9 Claims. (Cl. 103—161)

1

This invention relates to variable displacement pumps of the type employed to deliver liquid at closely regulated volumetric rates and it relates more particularly to a pump in which a plurality of cylinders are arranged radially in an inner rotor, a piston is fitted in each cylinder, the inner rotor is journaled upon a valve shaft or pintle which controls the flow of liquid to and from the cylinders, and an outer rotor is arranged around the inner rotor in engagement with the outer ends of the pistons to cause the pistons to reciprocate in the cylinders and to pump liquid when the rotors are rotated and are eccentric to each other. Pumps of this type are often employed in hydraulic feeding mechanisms of machine tools and are known as "feed pumps" when so employed.

When a pump is discharging liquid under a substantial pressure, the volume of liquid actually discharged is less than the displacement of the pump due to a number of small factors including liquid which passes across the face of the pump valve from the discharge port to the intake port, liquid which leaks out of the valve, liquid which escapes past the pump cylinders and distortion of parts of the pump due to creation of pressure. The difference between the displacement of the pump and the volume of liquid actually discharged is known as the "slip" of the pump. The pump ordinarily is connected to a hydraulic motor which also has "slip" and there may be slip in the channels which connect the pump to the motor. The difference between the pump displacement and the volume of liquid actually consumed in driving the motor is known as the "slip" of the system.

The slip is negligible when pump pressure is low and it increases as the pump pressure increases but the total slip at maximum pressure is only a very small percentage of the maximum volumetric capacity of the pump. Under certain conditions however, the rate at which a pump is required to deliver liquid may be no higher than the rate of slip when pump pressure is maximum. For example, a machine tool provided with a feed pump must often be adjusted to feed the tools into a workpiece at such a slow rate that the rate at which the pump must deliver liquid to produce that slow feed rate is less than the rate of slip when pump pressure is maximum. Ordinarily a moderate pressure is required to feed the tool into the workpiece but, if the stock being removed should increase in thickness or if the tool should strike a hard spot in the metal as often happens, pump pressure would rise substantially with a corresponding increase in slip. Consequently, unless means were provided to compensate for variations in slip, the increase in slip would cause the feed rate to decrease so much

2

that the workpiece when finished would be unsatisfactory.

Various means for compensating for slip have heretofore been proposed but all of the prior means are inaccurate, too expensive or too large and cumbersome for many installations.

The present invention has as an object to provide a pump which will accurately, simply and inexpensively compensate for variations in slip due to variations in pressure.

The cylinder barrel ordinarily is mounted upon the pintle with a very close running fit in order to keep the slip to a minimum and this arrangement is very satisfactory under most conditions but under certain conditions the cylinder barrel will seize upon the pintle.

A pump constructed according to the present invention has the advantage that it may have a greater clearance between the cylinder barrel and the pintle and thereby avoid or greatly reduce the danger of seizure.

Other objects and advantages will appear from the following description of the embodiments of the invention shown in the accompanying drawings in which the views are as follows:

Fig. 1 is a front view of a well known type of pump in which the invention is embodied, the frame of the pump having been omitted to simplify the view.

Fig. 2 is a longitudinal section partly in full taken on the slightly irregular line 2—2 of Fig. 1 and showing parts of the pump frame.

Fig. 3 is a transverse section taken on the line 3—3 of Fig. 2.

Fig. 4 is a transverse section partly in full taken on the line 4—4 of Fig. 2 but showing the rotors rotated to a position different from that shown in Fig. 2.

Fig. 5 is a section taken through the pintle only on the line 4—4 of Fig. 2 but drawn to a larger scale.

Fig. 6 is a vertical longitudinal section through another well known type of pump in which the invention is embodied, certain parts of the pump having been omitted to simplify the view.

Fig. 7 is a transverse section taken on the line 7—7 of Fig. 6.

The pumps have been shown with the pintle thereof arranged horizontally so that the rotors rotate in a vertical plane and they will be so described herein but it is to be understood that the terms used herein to designate positions and directions refer to the drawings only and in no way limit the invention as the pump may be mounted in different positions.

Figs. 1-5

The type of pump shown in these figures has been in extensive use for many years and it is

very similar to the pump shown in Patent No. 1,753,562 to which reference may be had for details of construction. Consequently, only so much of the pump has been shown as is necessary to an explanation of the invention.

The pump includes an outer rotor 1 which is keyed to a driveshaft 2 and is rotatably supported in a portion of a stationary frame 3 as by means of a bearing 4. An inner rotor or cylinder barrel 5 is arranged within outer rotor 1 and is journaled upon a valve shaft or pintle 6 which is supported in the same horizontal plane as shaft 2 by a pintle support or pendulum 7. Pintle 6 has one end portion thereof fixed within the lower portion of pendulum 7 and it is accurately located therein by a key 8. The upper portion of pendulum 7 is journaled upon a stationary shaft 9 which has the end portions thereof supported in portions of frame 3. The arrangement is such that pendulum 7 may be rocked upon shaft 9 to vary the displacement of the pump between zero and maximum as will presently be explained.

Shaft 9 has formed therein two passages 10 and 11 which extend radially inward in the plane of pendulum 7 and have been shown as extending axially from that plane through the front end of shaft 9 and as communicating, respectively, with two pipes 12 and 13 through which liquid flows to and from the pump. The radial ends of passages 10 and 11 register, respectively, with two passages 14 and 15 which are formed in pendulum 7 and are connected, respectively, by two pipes 16 and 17 to two other passages 18 and 19 which are formed in pendulum 7 above and below pintle 6. Pendulum 7 is rocked through such a small angular distance in adjusting pump displacement from zero to maximum that passages 14 and 15 remain nearly in complete registry with passages 10 and 11 respectively.

Passages 18 and 19 register, respectively, with two passages 20 and 21 which extend therefrom radially into pintle 6 and then extend axially thereof into communication with two ports 22 and 23 which extend radially inward from the peripheral surface of pintle 6. The unbroken portions of the pintle surface between the adjacent ends of ports 22 and 23 constitute "bridges" which have been designated in Figs. 4 and 5 by the reference numerals 24 and 25.

The inner rotor or cylinder barrel 5 has a plurality of equally spaced radial cylinders 26 formed therein, five being shown, and a cylinder port 27 extending through the inner end of each cylinder to communicate with pintle ports 22 and 23 alternately as cylinder barrel 5 rotates upon pintle 6.

Each cylinder has fitted therein a piston 28 which has been shown in Fig. 4 as including a hollow piston shell 29 which is closely fitted in cylinder 26 and a push rod 30 which is loosely fitted in shell 29 and is provided at its outer end with a crosshead 31 which is normal to the push rod axis. The inner face of each crosshead 31 rides upon two aligned surfaces 32 which are formed upon outer rotor 1 at right angles to a radius thereof. The outer face of each crosshead 31 engages a roller bearing 33 which rides upon a wear plate 34 arranged parallel to the adjacent surface 32 and fixed to outer rotor 1.

It will be obvious that, when the axis of pintle 6 and rotor 5 is offset toward the right from the axis of rotor 1 as shown and rotors 1 and 5 are rotated in a clockwise direction as indicated by the arrow on Fig. 4 the pistons 28 in

the lower half of rotor 5 will move progressively outward and will draw liquid into their cylinders through ports 27 and 23, passages 21 and 19, pipe 17 and passages 15 and 11 from pipe 13 and the pistons 28 in the upper half of rotor 5 will be forced progressively inward by outer rotor 1 and will eject liquid from their cylinders through ports 27 and 22, passages 20 and 18, pipe 16 and passages 14 and 10 into pipe 12 at a rate determined by the speed of the rotors and the distance that the axis of pintle 6 is offset from the axis of rotor 1. When the axis of pintle 6 is offset toward the left from the axis of rotor 1, the flow of liquid will be reversed. When the axes of pintle 6 and rotor 1 coincide, no reciprocation of the piston will occur and pump displacement will be zero.

While pintle 6 and the bore in cylinder barrel 5 have been shown as being straight, they are tapered in practice but the taper is so slight that it could not be shown in the drawing. Cylinder barrel 5 is prevented from moving rearward by rotor 1 and is prevented from moving forward by a shim or shims 35 arranged between its front end and pendulum 7 and of such thickness as to establish the proper running clearance between cylinder barrel 5 and pintle 6. Pendulum 7 is accurately located upon shaft 9 by shims 36 and 37 arranged between its ends and the adjacent portions of frame 3.

With the exception of the details of the bridges 24 and 25 on pintle 6, the pump as thus far described is substantially the same as the pump shown in Patent No. 1,753,562.

In the prior pump, the centerline of the bridges is on the horizontal centerline of the pintle and the circumferential length of each bridge ordinarily is slightly greater than the diameter of the cylinder ports to provide a positive seal between the two cylinder ports. According to the present invention and as shown in Fig. 5, the centerline of bridges 24 and 25 is rotated from the horizontal centerline of pintle 6 through a small angular distance in a direction opposite to the direction of rotation of the rotors and the circumferential length of each of bridges 24 and 25 is no greater than the diameter of a cylinder port 27.

Preferably, the ends of pintle ports 22 and 23 are arcuate as shown in Fig. 6 in which case the circumferential length of each bridge may be slightly less than the diameter of a cylinder port so that a cylinder port begins to open to one pintle port just as it moves out of communication with the other pintle port. The diameter of the cylinder port is so little greater than the length of a bridge and the cylinder barrel rotates so fast that there is substantially no flow of liquid from the high pressure pintle port to the low pressure pintle port as a cylinder port crosses a bridge but the arrangement provides quiet operation of the pump.

The forces exerted by the outer rotor upon the pistons to move them inward and to create pressure in the liquid are known as "pumping forces." When the pump is adjusted as shown and is discharging liquid under pressure into pintle port 22, the pumping force exerted upon a piston will be transmitted through the liquid to pintle 6 as soon as the port 27 of the cylinder containing that piston opens to port 22 and the force will continue to act upon pintle 6 until that cylinder port opens to pintle port 23. The pumping force will act directly downward upon pintle 6 when the cylinder is on the vertical centerline of the

pintle and it will act upon pintle 6 at an angle to the vertical centerline thereof when the cylinder is at either side of that centerline. The forces acting upon the pintle at the left of its vertical centerline are resolved into vertical components which tend to move the pintle downward and into horizontal components which tend to move the pintle toward the right and the forces acting upon the pintle at the right of its vertical centerline are resolved into vertical components which tend to move the pintle downward and horizontal components which tend to move the pintle toward the left.

If the centerline of the bridges were on the horizontal centerline of the pintle as in the prior pumps and if the length of each bridge did not exceed the diameter of the cylinder port, the horizontal components of the forces acting upon the pintle at one side of its vertical centerline would be substantially equal to the horizontal components of the forces acting upon the pintle at the other side of its vertical centerline so that there would be substantially no net force tending to move the pintle horizontally.

With the centerline of the bridges rotated from the horizontal centerline of the pintle through a small angular distance in a direction opposite to the direction of rotation of the rotor as indicated in Fig. 5, a cylinder in passing from one pintle port to the other pintle port opens to that other pintle port before the centerline of the cylinder crosses the horizontal centerline of the pintle. As soon as a cylinder port opens to the high pressure pintle port, a pumping force is transmitted through the liquid in that cylinder to the pintle and, as soon as a cylinder opens to the low pressure pintle port, the pumping force which had been transmitted to the pintle is destroyed. Consequently, the horizontal components of the pumping forces which urge the pintle in a direction to increase pump displacement exceed the horizontal components of the pumping forces which urge the pintle in a direction to decrease pump displacement.

For example, the port 21 of a cylinder passing across bridge 24 (Fig. 5) will open to pressure port 22 before the centerline of that cylinder passes across the horizontal centerline of the pintle and the port 27 of a cylinder passing across bridge 25 will open to suction port 23 before the centerline of that cylinder passes across the horizontal centerline of the pintle. Therefore, pintle 6 is subjected to pumping forces through a greater angular distance at the left of its vertical centerline than at the right thereof and, consequently, the horizontal components which urge pintle 6 toward the right or in a direction to increase pump displacement exceed the horizontal components which urge pintle 6 toward the left or in a direction to decrease pump displacement. The preponderance of force urging the pintle in a direction to increase pump displacement is utilized in compensating for variations in slip due to variations in pressure as will presently be explained.

The mechanism for swinging pendulum 7 upon shaft 9 to thereby vary pump displacement includes a spring arm 45 which is rigidly secured to pendulum 7. As shown, spring arm 45 is formed integral with an arm or link 46 which is fixed to pendulum 7 as by means of an extension 47 on pintle 6 and a bolt 48 both of which are closely fitted in link 46 and have suitable nuts on the outer ends thereof.

Spring arm 45 is provided at its lower end with

an abutment which has been shown as being a roller 49 mounted upon a shaft 50 and in engagement with a control element which has been shown as being a cam 51 mounted upon a control shaft 52. Roller 49 is held in contact with cam 51 by a spring 53 which tends to swing pendulum 7 toward the left. As shown, spring 53 has one of its ends connected to a rigid arm 54 which is formed integral with link 46 and its other end connected to an adjusting bolt 55 carried by a stationary support 56.

Spring arm 45 and spring 53 are so calibrated that spring 53 will positively hold abutment 49 in contact with control cam 51 at all adjustments of the pump and, when the pump is adjusted to discharge liquid into pipe 12 as previously explained, spring 53 will flex spring arm 45 as shown when pump pressure is zero and spring arm 45 will have sufficient strength to swing pendulum 7 in a direction to increase pump displacement when it is aided by the horizontal components of the pumping forces.

With the pump adjusted as shown, it will discharge liquid at a predetermined rate according to the adjustment of cam 51. When pump pressure rises, the horizontal components of the pumping forces will urge pintle 6 toward the right. The force thus exerted upon pintle 6 plus the force exerted by spring arm 45 overcomes the resistance of spring 53 sufficiently to move pintle 6 a slight distance toward the right and thereby increase pump displacement. Since the pumping forces are proportional to pump pressure, the horizontal components thereof are likewise proportional to pump pressure and, since the slip varies nearly in proportion to variations in pressure, the tension of spring 53 may be so adjusted by adjusting bolt 55 that pump displacement is increased by an amount substantially equal to the increase in slip due to the increase in pressure so that pump delivery remains substantially at the rate determined by the adjustment of cam 51. If thereafter pump pressure should decrease, the horizontal components of the pumping forces would correspondingly decrease and permit spring 53 to correspondingly decrease pump displacement.

If cam 51 were rotated through a sufficient angular distance to permit spring 53 to swing pendulum 7 far enough to move the axis of pintle 6 to the left of the axis of outer rotor 1, the pump would discharge liquid in the opposite direction and spring arm 45 would not deflect when pump pressure was zero. When the pump created pressure, the horizontal components of the pumping force would urge pintle 6 toward the left and the force exerted upon the pintle by the horizontal components of the pumping forces together with the force exerted by spring 53 would cause spring arm 45 to flex and permit pintle 6 to move toward the left to increase pump displacement and thereby compensate for the slip caused by the increase in pressure as explained above.

It previously has been pointed out that in prior feed pumps of this type the cylinder barrel ordinarily is mounted upon the pintle with a very close running fit in order to keep the slip at a minimum and that under certain conditions the cylinder barrel will seize upon the pintle.

When the temperature of the cylinder barrel is low and pump pressure suddenly increases, the heat generated due to the increase in pressure and to shearing the film of liquid between the cylinder barrel and the pintle causes the

metal adjacent to the mating surfaces of the cylinder barrel and the pintle to expand before the rest of the metal in the cylinder barrel becomes heated. Consequently, the heated metal of the cylinder barrel expands inward and reduces the running clearance. If the cylinder barrel has a close running fit upon the pintle as in the prior pumps, this reduction in the clearance will occasionally cause the cylinder barrel to seize upon the pintle, particularly if there are particles of foreign matter in the motive liquid.

Since a pump constructed according to the present invention automatically compensates for variations in slip due to variations in pressure, it is not necessary to keep the slip at the lowest possible minimum and the cylinder barrel may be fitted upon the pintle with sufficient clearance to avoid substantially all danger of seizure.

In the pump shown in Figs. 1-5 the outer rotor rotates on a stationary axis and the pintle is moved to vary pump displacement but the invention is also applicable to a pump in which the pintle is stationary and the outer rotor is moved to vary pump displacement.

Figs. 6 and 7

The pump shown in these figures is also a well known type and, except that the pistons and cylinders have been shown as being on radii of the cylinder barrel instead of being inclined to those radii, the pump is similar to the pump shown in Patent No. 2,105,454 to which reference may be had for details of construction. Consequently, only so much of the pump has been shown as is necessary to illustrate the application of the invention thereto.

The pump has an inner rotor or cylinder barrel 61 journaled upon a valve shaft or pintle 62 which is rigidly supported in a stationary position by having one end portion thereof fixed in a portion of the pump frame or case 63 only portions of which have been shown.

The portion of pintle 62 upon which cylinder barrel 61 is journaled is substantially the same as the corresponding portion of pintle 6 shown in Figs. 2-5. That is, it has two diametrically opposed pintle ports 64 and 65, which correspond to ports 22 and 23, and the unbroken surface of the pintle between adjacent ends of the pintle ports constitute bridges 66 and 67 which correspond to bridges 24 and 25 and have the centerline thereof rotated through a short angular distance from the horizontal centerline of the pintle in a direction opposite to the direction of rotation of cylinder barrel 61. Pintle 62 has formed therein two passages 68 and 69 which extend axially rearward from ports 64 and 65, respectively, and then extend radially outward into communication, respectively, with two passages 70 and 71 which are formed in case 63 and are adapted to be connected, respectively, to a hydraulic circuit as by means of pipes 72 and 73.

Cylinder barrel 61 has formed therein a plurality of radial cylinders 74 and an equal number of cylinder ports 75 each of which extends through the inner end wall of a cylinder and is adapted to register with pintle ports 64 and 65 alternately as cylinder barrel 61 rotates. Rotation of cylinder barrel 61 is effected by a drive shaft 76 which is connected thereto by a coupling 77. Shaft 76 is journaled in suitable bearings (not shown) and preferably is also journaled in the end of pintle 62 as indicated in dotted lines in Fig. 6.

A piston 78 is closely fitted for reciprocation

in each cylinder 74 and it has its outer end beveled to engage a beveled reaction surface 79 carried by an outer rotor 80 which is arranged within a hollow support or slide block 81 and is rotatably supported therefrom by two bearings 82 and 83.

Slide block 81 has fixed to the top and bottom thereof four wear plates 84 each of which engages a wear plate 85 which is fixed to case 63. The rear end of slide block 81 engages the rear wall of case 63 and the front end thereof engages a partition plate 86 which is fixed in case 63 near the front end thereof. The arrangement is such that slide block 81 is prevented from moving vertically or axially of pintle 62 but it may be moved transversely of pintle 62 to vary pump displacement.

As shown, slide block 81 is urged toward the right by a spring 87 and it is adapted to be moved toward the left by a link or arm 88 which is pivoted intermediate its ends upon a bolt 89 carried by lug 90 which is fastened to slide block 81. Arm 88 is journaled at its upper end upon a bolt 91 carried by case 63 and its lower portion is formed into a spring arm 92 which carries at its lower end an abutment shown as being a roller 93 journaled upon a bolt 94. Roller 93 is engaged by a control element shown as being a cam 95 fixed upon a control shaft 96.

When cam 95 is adjusted to move slide block 81 toward the left until the axis of outer rotor 80 is at the left of the axis of pintle 62 as shown in Fig. 7 and rotor 61 is rotated clockwise as indicated by the arrow on Fig. 7, the pistons 78 in the lower half of cylinder barrel 61 will move progressively outward, the pistons 78 in the upper half of cylinder barrel 61 will be forced progressively inward by outer rotor 80, liquid will flow from pipe 73 through passages 71 and 69 and ports 65 and 75 into the cylinders containing outward moving pistons and the inward moving pistons will force liquid from their cylinders through ports 75 and 64 and passages 68 and 70 into pipe 72. If the axis of outer rotor 80 were at the right of the pintle axis, the flow of liquid would be reversed. When slide block 81 is in its neutral position in which the axis of rotor 80 coincides with the pintle axis, no reciprocation of the pistons will occur and pump displacement will be zero.

When the pump is creating pressure, the horizontal components of the pumping forces tend to effect relative movement between the pintle and the outer rotor. In the pump shown in Figs. 1-5, the outer rotor cannot be moved horizontally and the horizontal components of the pumping forces tend to move the pintle. In the pump shown in Figs. 6 and 7, pintle 62 is fixed and the horizontal components of the pumping forces tend to move outer rotor 80 and slide block 81 which supports it.

With slide block 81 at the left of its neutral position as shown and with the pump discharging liquid under pressure into pipe 72, the horizontal components of the pumping forces at the left of the vertical centerline of pintle 62 will tend to move slide block 81 toward the left and the horizontal components of the pumping forces at the right of the vertical centerline of pintle 62 will tend to move slide block 81 toward the right. Since the centerline of bridges 66 and 67 is rotated a short angular distance from the horizontal centerline of the pintle in a direction opposite to the direction of rotation of the rotors, the horizontal components of the pump-

ing forces at the left of the vertical centerline of the pintle will exceed the horizontal components of the pumping forces at the right thereof and slide block 81 will be urged toward the left by the preponderance of force equal to the difference between the horizontal components on opposite sides of the pintle centerline.

Spring 87 and spring arm 92 are so calibrated that spring 87 will positively hold abutment 93 in contact with control element 95 at all adjustments of the pump and spring arm 92 will be flexed as shown when slide block 81 is moved toward the left beyond its neutral position and pump pressure is zero. When pump pressure rises, the horizontal components of the pumping forces will urge slide block 81 toward the left and the force thus exerted upon slide block 81 plus the force exerted by spring arm 92 overcomes the resistance of spring 87 sufficiently to move slide block 81 enough farther toward the left to increase pump displacement sufficiently to compensate for the increase in slip due to the increase in pressure as previously explained in connection with the description of the pump shown in Figs. 1-5.

The invention disclosed herein is susceptible of other modifications and adaptations without departing from the scope of the invention which is hereby claimed as follows.

I claim:

1. A pump comprising an outer rotor rotatable in a vertical plane, a support for said rotor, a pintle extending into said outer rotor and provided with diametrically opposed intake and discharge ports and with axial passages communicating with said ports, the adjacent ends of said ports being separated from each other by unbroken portions of the peripheral surface of said pintle which constitute bridges to provide seals between said ports, an inner rotor journaled upon said pintle and provided with a plurality of equally spaced radial cylinders and with an equal number of cylinder ports each of which extends through the inner end wall of a cylinder to communicate with said pintle ports alternately as said inner rotor rotates, a support for said pintle, one of said supports being movable in respect to the other support to move one of said rotors between a position in which the axes of said rotors are coincident and the displacement of said pump is zero and a position in which the axes of said rotors are offset from each other and the displacement of said pump is maximum, a piston fitted in each of said cylinders and having the outer end thereof in engagement with said outer rotor, means for rotating one of said rotors, rotation of one rotor causing rotation of the other rotor due to engagement of said pistons with said outer rotor and also causing said pistons to reciprocate in said cylinders and to pump liquid when the axes of said rotors are offset from each other, a control arm connected to one of said supports, a spring arm fixed to said control arm, an abutment carried by the free end of said spring arm, a control element normally engaging said abutment and adjustable to move said arm in a direction to increase pump displacement, and a spring to urge said movable support in the opposite direction and to hold said abutment in engagement with said control element, said pintle bridges being rotated through a small angular distance from the horizontal centerline of said pintle in a direction opposite to the direction of rotation of said rotors to thereby cause horizontal components of the pumping forces to urge said

pintle toward its maximum displacement position.

2. A pump comprising an outer rotor rotatable in a vertical plane, a support for said rotor, a pintle extending into said outer rotor and provided with diametrically opposed intake and discharge ports and with axial passages communicating with said ports, the adjacent ends of said ports being separated from each other by unbroken portions of the peripheral surface of said pintle which constitute bridges to provide seals between said ports, an inner rotor journaled upon said pintle and provided with a plurality of equally spaced radial cylinders and with an equal number of cylinder ports each of which extends through the inner end wall of a cylinder to communicate with said pintle ports alternately as said inner rotor rotates, a support for said pintle, one of said supports being movable in respect to the other support to move one of said rotors between a position in which the axes of said rotors are coincident and the displacement of said pump is zero and a position in which the axes of said rotors are offset from each other and the displacement of said pump is maximum, a piston fitted in each of said cylinders and having the outer end thereof in engagement with said outer rotor, means for rotating one of said rotors, rotation of one rotor causing rotation of the other rotor due to engagement of said pistons with said outer rotor and also causing said pistons to reciprocate in said cylinders and to pump liquid when the axes of said rotors are offset from each other, a control arm having one portion thereof connected to said movable support and another portion thereof divided into a rigid arm and a spring arm, an abutment carried by the free end of said spring arm, a control element normally engaging said abutment and adjustable to move said arm in a direction to increase pump displacement, and a spring connected to said rigid arm to urge said pintle support in the opposite direction and to hold said abutment against said control element, said pintle bridges being rotated through a small angular distance from the horizontal centerline of said pintle in a direction opposite to the direction of rotation of said rotors to thereby cause horizontal components of the pumping forces to urge said pintle toward its maximum displacement position.

3. A pump according to claim 2 in which the angular distance between the adjacent ends of said pintle ports is no greater than the angular length of said cylinder ports.

4. A pump comprising an outer rotor rotatable in a vertical plane, means for rotating said rotor, a pintle extending into said outer rotor and provided with diametrically opposed intake and discharge ports and with axial passages communicating with said ports, the adjacent ends of said ports being separated from each other by unbroken portions of the peripheral surface of said pintle which constitute bridges to provide seals between said ports, an inner rotor journaled upon said pintle and provided with a plurality of equally spaced radial cylinders and with an equal number of cylinder ports each of which extends through the inner end wall of a cylinder to communicate with said pintle ports alternately as said inner rotor rotates, a piston fitted in each cylinder, means for transmitting motion from said outer rotor to said pistons to thereby cause said inner rotor to rotate in unison with said outer rotor and also to cause said pistons to reciprocate in their cylinders and to pump liquid when the axis of said pintle is offset from the

11

axis of said outer rotor, a support for said pintle movable horizontally between a position in which the axis of said pintle coincides with the axis of said outer rotor and the displacement of said pump is zero and a position in which the axis of said pintle is offset from the axis of said outer rotor and the displacement of said pump is maximum, a spring arm having one end portion thereof fixed to said pintle support, an abutment carried by the free end of said spring arm, a control element normally engaging said abutment and adjustable to move said arm and said pintle in a direction to increase pump displacement, and a spring to urge said pintle support in the opposite direction and to hold said abutment in engagement with said control element, said pintle bridges being rotated through a small angular distance from the horizontal centerline of said pintle in a direction opposite to the direction of rotation of said rotors to thereby cause horizontal components of the pumping forces to urge said pintle toward its maximum displacement position.

5. A pump according to claim 4 in which the angular distance between the adjacent ends of said pintle ports is no greater than the angular length of said cylinder ports.

6. A pump comprising an outer rotor rotatable in a vertical plane, means for rotating said rotor, a pintle extending into said outer rotor and provided with diametrically opposed intake and discharge ports and with axial passages communicating with said ports, the adjacent ends of said ports being separated from each other by unbroken portions of the peripheral surface of said pintle which constitute bridges to provide seals between said ports, an inner rotor journaled upon said pintle and provided with a plurality of equally spaced radial cylinders and with an equal number of cylinder ports each of which extends through the inner end wall of a cylinder to communicate with said pintle ports alternately as said inner rotor rotates, a piston fitted in each cylinder, means for transmitting motion from said outer rotor to said pistons to thereby cause said inner rotor to rotate in unison with said outer rotor and also to cause said pistons to reciprocate in their cylinders and to pump liquid when the axis of said pintle is offset from the axis of said outer rotor, a support for said pintle movable horizontally between a position in which the axis of said pintle coincides with the axis of said outer rotor and the displacement of said pump is zero and a position in which the axis of said pintle is offset from the axis of said outer rotor and the displacement of said pump is maximum, a control arm having one end portion thereof fixed to said pintle support and the other portion thereof divided into a spring arm and a rigid arm, an abutment carried by the free end of said spring arm, a control element normally engaging said abutment and adjustable to move said arm and said pintle in a direction to increase pump displacement, and a spring connected to said rigid arm to urge said pintle support in the opposite direction and to hold said abutment against said control element, said pintle bridges being rotated through a small angular distance from the horizontal centerline of said pintle in a direction opposite to the direction of rotation of said rotors to thereby cause horizontal components of the pumping forces to urge said pintle toward its maximum displacement position.

7. A pump according to claim 6 in which the

12

angular distance between the adjacent ends of said pintle ports is no greater than the angular length of said cylinder ports.

8. A pump comprising an outer rotor rotatable in a vertical plane, means for rotating said rotor, a pintle extending into said outer rotor and provided with diametrically opposed intake and discharge ports and with axial passages communicating with said ports, the adjacent ends of said ports being separated from each other by unbroken portions of the peripheral surface of said pintle which constitute bridges to provide seals between said ports, an inner rotor journaled upon said pintle and provided with a plurality of equally spaced radial cylinders and with an equal number of cylinder ports each of which extends through the inner end wall of a cylinder to communicate with said pintle ports alternately as said inner rotor rotates, a piston fitted in each cylinder, means for transmitting motion from said outer rotor to said pistons to thereby cause said inner rotor to rotate in unison with said outer rotor and also to cause said pistons to reciprocate in their cylinders and to pump liquid when the axis of said pintle is offset from the axis of said outer rotor, a shaft arranged in a stationary position above said outer rotor and provided with passages for connection to an external circuit, a pendulum having the upper end portion thereof journaled upon said shaft and having said pintle fixed in the lower end portion thereof to thereby support said pintle and said inner rotor, said pendulum being swingable upon said shaft to move said pintle between a position in which the axis of said pintle coincides with the axis of said outer rotor and the displacement of said pump is zero and a position in which the axis of said pintle is offset from the axis of said outer rotor and the displacement of said pump is maximum, a control arm having one end portion thereof fixed to said pendulum and the other portion thereof divided into a spring arm and a rigid arm, an abutment carried by the free end of said spring arm, a control element normally engaging said abutment and adjustable to move said arm and said pintle in a direction to increase pump displacement, and a spring connected to said rigid arm to urge said pintle support in the opposite direction and to hold said abutment against said control element, said pintle bridges being rotated through a small angular distance from the horizontal centerline of said pintle in a direction opposite to the direction of rotation of said rotors to thereby cause horizontal components of the pumping forces to urge said pintle toward its maximum displacement position.

9. A pump according to claim 8 in which the angular distance between the adjacent ends of said pintle ports is no greater than the angular length of said cylinder ports.

JAMES K. DOUGLAS.
